ETHAN POSTLE, OF LINTON, NORTH DAKOTA.

AUTOMATIC BOILER FEED MECHANISM.

1,253,093.

Specification of Letters Patent.

Patented Jan. 8, 1918.

Application filed May 15, 1917. Serial No. 168,766.

To all whom it may concern:

Be it known that I, ETHAN POSTLE, a citizen of the United States, residing at Linton, in the county of Emmons and State of 5 North Dakota; have invented new and useful Improvements in Automatic Boiler Feed Mechanisms, of which the following is a specification.

This invention relates to automatic feed 10 devices for boilers and more particularly to a float controlled mechanism which operates when the water is above or below a predetermined level to actuate an injector.

One of the objects of the invention is to 15 provide an automatic boiler feed comprising a pair of steam lines leading upwardly through the water in a boiler and terminating above the water level, the flow of steam through said lines being governed by individual valves operated by float mechanism, the valve being opened at different times to 20 feed the steam to an engine for opening or closing an injector valve.

The invention also aims to generally improve 25 automatic feed mechanism for boilers to render it more practical, useful, efficient and commercially desirable.

With these and other objects in view as will become more apparent as the description 30 proceeds, the invention consists in certain novel features of construction, combination and arrangement of parts as will be hereinafter fully described, illustrated and claimed.

35 In the drawings,

Figure 1 is a side elevation of the device as it appears in use with the boiler shown in dotted lines.

Fig. 2 is a perspective view of that part 40 of the mechanism housed within the boiler.

Fig. 3 is a longitudinal sectional view through one of the valves showing the operating lever therefor.

Fig. 4 is a transverse sectional view 45 through the valves.

Fig. 5 is a longitudinal sectional view through the steam engine.

Fig. 6 is a perspective view of the float 50 operated levers and float, and

Fig. 7 is a longitudinal sectional view 55 similar to Fig. 3 showing the other valve from that shown in Fig. 3.

Referring in detail to the drawings by numerals, 1 designates a steam boiler which 60 is supplied with water through the steam injector pipe 2 which latter is supplied with

steam by the pipe 3 having an injector valve 4 equipped with a handle 5. My invention aims to provide a simple and practical automatic mechanism for opening and closing 60 the injector valve to maintain the water level practically constant within the boiler.

In the preferred embodiment of my device, I provide a pair of steam lines generally designated 6 and 7 which lead upwardly through the water within the boiler to a termination thereabove. Forming a part of each of the steam lines is a valve casing 8. These casings are cylindrical, are closed at their upper ends and are connected 70 vertically within the boiler to the end thereof by the arms or braces 9. The casings are each formed on their lower ends with right angle extensions 10 which are engaged with the exit openings 11 through the boiler as 75 shown. This manner of connecting the extensions provides a further support for the vertical valve casings. Cylindrical sleeve valves 12 and 13 operate respectively within the casings and are each formed with an external series of teeth 14 providing racks.

The valve casings are formed with slots or openings 15 opposite the racks so that the latter may be engaged by the segmental toothed heads of the float operated levers 16. 85 These levers are pivoted on trunnions 17 carried by arms 18 fixed to a connecting bracket 19 between the valve casings as illustrated. The long arms of the levers are secured to a float 20 and the short arms are 90 formed on their terminals with the segmental heads 21 provided with the gear teeth 22 which mesh with the teeth 14, of the racks.

A movement of the float in response to a 95 change of water level causes the levers 16 to move the valves longitudinally. The valve 12 is formed with a port 23 near its upper end which is adapted for registration with a port 24 in the corresponding valve casing 100 and the valve 13 is provided with a port 25 adapted for registration with the port 26 in the other valve casing. These ports are each connected to steam pipes 27 forming a part of the steam lines 6 and 7. 105

When the water level in the boiler is at the desired or normal height, the float controlled levers 16 hold the valves in a neutral closed position at which time they are so arranged as to dispose the port 23 above the 110 port 24 and the port 25 below the port 26. Now it is apparent, that sufficient drop in

water level will elevate the valves and register the port 25 with the port 26, and that a rise of water level above normal will lower the valves to close the port 26 and open the port 24.

Steam flowing through the valves is conducted to an engine 28 by means of the pipes 29 and 30. The engine comprises a cylinder 31 having the intake ports 32, 33 and 10 the discharge ports 34, 35, the intake ports being preferably in the side of the cylinder and the discharge ports being in the end thereof. Within the cylinder is a piston 36 having the piston or valve rods 37 and 38 15 which extend through the exhaust ports and which carry respectively, the valves 39 and 40. The rod 37 connects with the turning lever 41 on the injector valve rod 5. Clamps 42 connect the cylinder to the steam line 3.

20 When the float 20 drops to open the port 26, steam will flow through the steam line 7 into the cylinder 31 through the port 33 and force the piston 36 to the left to open the injector valve, whereupon the water will 25 be injected into the boiler. When the piston has been moved sufficiently far to open the injector valve, the valve 39 will have closed the exhaust port 35 to prevent further escape of steam from the boiler. When the 30 water level reaches normal or exceeds the same, the float 20 will raise to close the port 26 and open the port 24. Steam flowing through the port 24 will be conducted to the port 32 of the cylinder 31 and move the piston therein to the right to close the injector 35 valve as will be clearly understood.

From the foregoing description taken in connection with the accompanying drawings, it will be apparent that I have devised a 40 very practical and efficient automatic boiler feed mechanism which is controlled by the water level within the boiler and which will maintain this level at a practical constant height within small limits.

45 While I have shown and described the preferred embodiments of my invention, it will be clearly understood that I do not wish to be limited to this construction, but may make such changes as will fall within 50 the scope and spirit of the invention as claimed.

What I claim is:

1. In a feed control mechanism for boilers, a pair of steam lines extending upwardsly through the boiler from below the 55 normal water level to a termination above the same, valve casings in said steam lines having ports connected therewith, valves slidable within said casings to close said 60 ports to prevent a flow of steam through

the steam lines and float operated means for moving said valves to open these ports in response to a change of water level within the boiler, a drop in water level causing one port to be opened and the other closed and 65 a rise in water level causing a reverse action, and means operated by steam flowing through the steam lines to actuate an injector valve.

2. In an automatic boiler feed mechanism, 70 a pair of steam lines running upwardly through the boiler and terminating above the maximum water level thereof, a cylindrical valve casing in each of said steam lines, a sleeve valve slidable within each of 75 said casings and having a port adapted to be registered with the port of the casing, rack teeth formed on each of the sleeve valves, the valve casings being slotted opposite said rack teeth, and float controlled 80 levers pivoted intermediate their ends, each of said levers being provided with a toothed segmental head on one terminal for engagement with one of the racks.

3. In an automatic feed control for boilers, a pair of vertical valve casings mounted within the boiler, each casing being formed with an intake port, a steam pipe connecting with each intake port, the casings being closed at their upper ends and opened at 90 their lower ends, steam pipes connected to the lower ends of the casing and leading to the exterior of the boiler, means supplied with steam from said pipes for actuating an injector valve, a sleeve valve slidable 95 within each of said valve casings, float controlled means for actuating said valves, the valves being so arranged that a drop in water level will admit steam to one of the valve casings and that a rise in water level 100 will admit steam to the other of the valve casings.

4. In an automatic feed control for boilers, a pair of vertical valve casings mounted within the boiler, said casings being closed 105 at their upper ends, pipes connected to the lower ends of the casings and leading to the exterior of the boiler, sleeve valves slidable within said casings and formed with ports adapted to register with ports of the 110 casings, float controlled means for actuating the valves to admit steam into one of the casings when the water level drops below normal and to admit steam into the other of the casings when the water level 115 rises above normal and means actuated by steam flowing through said casings for controlling an injector valve.

In testimony whereof I affix my signature.

ETHAN POSTLE.
